UNITED STATES PATENT OFFICE.

STEWART BROWN, OF CHICAGO, ILLINOIS.

ELECTRIC LIGHTER FOR GAS-BURNERS.

1,026,848.

Specification of Letters Patent.

Patented May 21, 1912.

Application filed December 30, 1911. Serial No. 668,624.

To all whom it may concern:

Be it known that I, STEWART BROWN, a citizen of the United States, residing at Chicago, in the county of Cook and State of Illinois, have invented certain new and useful Improvements in Electric Lighters for Gas-Burners, of which the following is a specification.

This invention relates to electric means for lighting gas, generated from calcium carbid or contained in a tank, as the same flows from a burner tip.

The object of the invention is to obtain a device which can be applied to lamps which are already in use, which will be economical in construction and installation, which consists of few parts, not liable to get out of order or to be injured, and a device by means of which the gas flowing from the tips of the burners of said lamps will be ignited by the heat generated in a resistance coil by a low voltage electric current on the circuit of which the device forms an element.

In the drawing Figure 1 is an elevation of a burner and of a device embodying this invention mounted thereon. Fig. 2 is a top plan view of the burner and device. Fig. 3 is a vertical section of the base of the device on line 3—3 of Fig. 4, viewed in the direction indicated by the arrows. Fig. 4 is a top plan view of the base of the device. Fig. 5 is a vertical section of the base viewed as in Fig. 3, with an elevation of some of the electric conductors forming elements of the device secured in said base. Fig. 6 is an elevation of tubes forming elements in the device, viewed at an angle of 90 degrees from the view thereof illustrated in Fig. 1, with a resistance coil forming an element of the device mounted thereon.

The several figures of the drawing are on a scale much larger than the parts represented thereby.

Similar letters refer to similar parts throughout the several views.

A is an ordinary acetylene burner provided with stem a and tips a' and apertures a'', a''' in said tips.

B, B, are metal tubes respectively provided with bends b, b', b'', and b'''.

C are metal wires forming electric conductors which are attached at their upper ends to the lower ends of the respective tubes B. Wires C are provided with bends c' and C'.

D is a resistance coil. The ends d of coil D are inserted in the upper ends of tubes B.

E is a base made of fiber or other insulating material. Base E is provided with groove e on the upper side thereof, (see Figs. 2, 3 and 4), with apertures e' therethrough and with grooves e'' on the under side thereof. Grooves e'' are parallel and at right angles to the groove e. The apertures e' and in grooves e and e''.

e''' are holes or wells communicating with grooves e'' respectively.

F is a band around the stem of burner A and around base E.

G is a thumb bolt extending through band F and through nut g. The inner end of the thumb bolt G is forced against the base E by turning it in one direction in nut g and retracted from said base on turning it in the opposite direction. The nut g is preferably attached to the inner face of one end of band F, as by solder, to prevent its loss when the device is being secured to a burner tip. The front face of base E, lettered H in Fig. 4, is curved to fit reasonably close to the stem of burner tip A.

I is an insulating covering to wire C.

To assemble the device the tubes B are taken (bends b', b'', having been previously made) and the lower ends thereof are inserted through apertures e' in base E so that said bends b', b'', are in groove e. The wires C are taken (the ends thereof having been previously stripped of the insulating cover and bends C' and C'' made therein); and inserted in holes or wells e''' so that bends C', C'' are in grooves e''. The lower ends of tubes B are then bent over onto wires C in grooves e'' (making thereby bends b''' in tube B) and soldered together. The ends d of resistance coil D are inserted in the upper ends of tubes B (fitting closely therein), and bend b is made in said tubes and like bends are thereby made in ends d. Ends d may be soldered in tubes B to make good electric connections, but if at any time when the device is in use the upper ends of the tubes become so hot as to melt said solder (from the heat of the flame of the gas from apertures a''), the ends d will be held in tubes B by bends b, and on the cooling of said tubes the solder will again congeal.

The band F bent as described and having nut g attached to one end thereof is put in place on base E, and thumb bolt G is inserted in said nut.

To install the device the thumb nut G is removed and band F, which is made of ductile metal, is bent so as to pass over stem a of burner A, and the device is adjusted so 5 that the resistance coil D is between the tips a', and in substantially the position illustrated in Figs. 1 and 2 of the drawing. The thumb bolt G is then inserted in apertures provided therefor in the ends of band F and 10 screwed into nut g until the end thereof presses firmly against base E thereby securing the device firmly to the burner. The resistance coil D is made of a wire of small diameter and presenting suitable resistance 15 to an electric current so that it is heated by a current of about six volts sufficiently to ignite acetylene gas flowing from apertures a''.

To use the device the wires C are put into 20 a circuit having an electric generator therein (a 6-60 storage battery or four primary cells connected in series), and after directing a flow of gas through the burners the circuit is closed. The gas will be thereby 25 ignited. As the circuit of which this device is an element is closed only when the gas from the burners is to be ignited when the device is attached to the burners of an automobile the batteries which are used for 30 making the spark to ignite the fuel mixtures in the several cylinders of the engine of said automobile may be also used as the electric generator which supplies the current to operate this device.

35 I claim:—

1. In an electric igniter for gas burners

the combination of a base made of insulating material, and provided with a groove on the upper side thereof, grooves on the under side thereof, and apertures, electric conducting wires provided with bends, standards made of metal tubes and provided with bends, said wires and standards inserted in the apertures and grooves of the base and electrically joined to each other, a resistance coil the ends whereof are inserted in the ends of the standards, and electrically joined thereto, a band of ductile metal and a thumb screw, said band arranged to secure the base in a determined position on 40 turning said thumb screw in a given direction. 45

2. In an electric igniter for gas burners, a base made of insulating material and provided with grooves and apertures, wires 55 provided with bends, metal standards provided with bends and with apertures in the upper end thereof, said wires and standards mounted in said grooves and apertures in the base and electrically joined together, and a resistance coil electrically connected to the standards with the ends thereof in said apertures in the standards, in combination with a band, a nut and a thumb screw, said band, nut and thumb screw co-acting with 60 65 said base to secure said base in a determined position.

STEWART BROWN.

In the presence of—

CHARLES TURNER BROWN,
CORA A. ADAMS.
